L. STOLTENBERG

NECKWEAR HOLDER

Filed Sept. 6, 1927

FIG. I.

25

FIG. 2

FIG. 3.

INVENTOR.

BY
Louis Stoltzenberg

UNITED STATES PATENT OFFICE.

LOUIS STOLLENBERG, OF OAKLAND, CALIFORNIA.

NECKWEAR HOLDER.

Application filed September 6, 1927. Serial No. 217,591.

This invention relates to improvements in neckwear racks, or stands, for use in connection with men's wardrobes.

The present invention is a comparatively cheap form of rack, or stand, and is somewhat similar in form to that shown in my co-pending application for combination collar box and neckwear holder, filed September 6, 1927, Serial No. 217,592, except that the present construction is formed from wire and is considerably simplified in construction and consequently less expensive to produce.

The object of the present invention is to provide a rack, or stand, of the class designated, which is formed from wire to produce a simple, durable and compact article-supporting means for collars and neckties.

Another object of my invention is to produce a rack, or stand, of the class indicated which is provided with a revoluble necktie holder of simple form arranged to hold a number of neckties in segregated relation, so that any selected necktie may be readily removed therefrom or replaced thereon.

Other objects and advantages of my invention will be apparent with reference to the subjoined specification and accompanying one sheet of drawings, in which:

Figure 1 is a perspective view illustrating the preferred form of my invention and showing the relative arrangement of the collar support, necktie holder and supporting brace therefor;

Figure 2 is an enlarged sectional detail illustrating the method of forming the necktie holder;

Figure 3 is an enlarged sectional detail of one of the necktie engaging clips of the necktie holder, the section being indicated by the line 3—3 in Figure 1; and

Figure 4 is a plan section illustrating the necktie holder.

It will be observed with reference to the drawings that the entire rack is formed from medium gauge wire which provides a cheap yet strong and durable article for the purpose specified. In detail the rack consists of an upright support 5 having secured to its upper end a plurality of upwardly and outwardly curved arms 6, providing braces for a collar supporting ring 7 to which the ends of the arms 6 are "spot welded" as indicated at 8. The lower ends 9 of the arms 6 being preferably "spot welded" to the upper end of the support 5 as indicated at 10.

The supporting bracket 11 consists of a

pair of strands of wire spot-welded together and bent to form the arms 12 and 13, supporting member 14, screw loops 15 and 16, and twisted ends forming support-embracing loops 17 and 18, in which loops the support 5 is adapted to freely rotate. The member 14 of the bracket is placed against any object, such as the wall of a room, and screws or nails are inserted in the loops 15 and 16 and driven home, which holds the support 5 in a vertical position, as shown in Figure 1.

The lower end of the support 5 carries a necktie holder 19 which holder consists of a ring 20 provided with a cross piece 21 which is "spot welded" thereto and in turn is welded to the lower end of the support 5 as indicated at 22.

The necktie holding-members proper are formed from a single piece of wire looped to form the various holders 23, which holders consist of the wire sections 24 looped at their outer ends 25 and providing a centrally disposed ring 25^a of somewhat smaller diameter than the ring 20. The inner sections 26 and 27 of the holders are "spot welded" to the upper side of the ring 20 and both rings are rigidly carried by the cross piece 21 as shown.

Spring clips 28 having their inner ends preferably "spot welded" to the ring 20, between the ends 26 and 27 of the supporting arms are provided, and extend outwardly between these arms and are bent upwardly at their outer ends 29, the looped ends 25 of the arms being bent downwardly, as indicated at 30 to widen the space between the ends 29 of the clips 28 and said looped ends 25, so that a necktie may be readily inserted between the clips and supports.

The ring 7 provides a support for any number of collars 31, which may be hung in position, as shown in dot-and-dash lines and the necktie holder 19 provides holders for, at least four neckties 32, as shown in dot-and-dash lines in Figure 1. The ring 7, support 5 and holder 19 rotate as a unit in the bearing loops 17 and 18.

An article of the class described constructed in accordance with my invention, provides a handy rack, or stand, which may be attached in any convenient place near a dresser, or it may be attached directly to the dresser or any other article of furniture.

While I have shown and described the preferred embodiment of the invention it is, of course, to be understood that I reserve the right to make such changes in the form, con-

structions and arrangement of parts as will not depart from the spirit of the invention or the scope of the subjoined claims.

Having thus described my invention, I claim:

- 5 1. An article of the class described, comprising a wire-supporting-frame adapted for revoluble mounting upon a suitable object and consisting of an upright member having a necktie holder rigidly mounted at its lower end and embodying a ring having a plurality of radially disposed supporting arms forming holders, said arms consisting of a single looped strand the inner sections of which are 10 "spot welded" to the upper face of said ring and having their outer looped ends bent downwardly, and spring clips consisting of single wires having their inner ends "spot welded" to said ring between the extremities 15 of said looped holders and their outer ends bent in opposition to the downwardly bent sections of said holders and adapted to co-

act therewith in holding articles securely in place upon said holders.

- 25 2. An article of the class described, comprising a wire-supporting frame adapted for revoluble mounting upon a suitable object and consisting of a vertically disposed rod bearing at its lower end a necktie holder embodying a ring having a cross-piece welded to the lower end of said rod and providing a support for a cross-shaped holder-member, said holder-member consisting of a plurality of article-supporting arms embodying a central ring and outwardly looped members having their extremities bent downwardly, and spring-clips having their inner ends secured to the underside of said first mentioned ring and adapted to coact with said looped arms in retaining articles inserted thereon.

30 35 40 In testimony whereof I have hereunto affixed my signature.

LOUIS STOLTENBERG.
